UNITED STATES PATENT OFFICE.

ELMER HEDEEN, OF MANSFIELD, OHIO, ASSIGNOR TO THE HUGHES-KEENAN COMPANY, OF MANSFIELD, OHIO, A CORPORATION OF OHIO.

METALLIC STAIR.

Application filed November 10, 1927. Serial No. 232,414.

This invention relates to metal stairs, and among other objects, aims to provide a readily manufactured and assembly stair construction which is distinguished by its economy.

5 In the accompanying drawings wherein is shown a preferred form of the invention:

Fig. 1 is a vertical sectional elevation of a portion of a stairway embodying the invention;

10 Fig. 2 is a section on line 2—2 of Fig. 1;

Fig. 3 is a detail section to illustrate the way the parts of the stairs are assembled; and

15 Fig. 4 is a fragmentary view in perspective showing one of the locking tangs by which the parts of the stairs are held together when assembled.

In accordance with the invention, a plurality of like metallic members, preferably 20 formed of sheet metal, are assembled and secured to a pair of metal stringers, which provide the primary support for the steps. Each metallic step member consists of a 25 tread portion and a riser portion, and each of said portions interlock with the riser and tread portions, respectively, of the next lower and higher step members. The interlocking is secured by the peculiar shape of the parts, and the way they are assembled, and by a plurality of tangs integrally formed on each 30 riser portion and providing abutments for the adjacent tread portion, when the parts are assembled. The resultant construction prevents relative movement of the steps, with a 35 minimum number of bolts or other fastening elements, and without the necessity of any additional labor in manufacture of the steps, such as welding a locking member in position.

40 Referring more particularly to the drawings there is shown a portion of a stairway including stringers 5 each having a lower inwardly projecting flange 6 to which the step members, to be described, are secured as by 45 screws 7 (Fig. 1), preventing slight movements longitudinally or transversely of the stringers. The stringers are drawn together by rods 8 having nuts 9; when the nuts are tightened, the stringers clamp the step members, preventing play in the joints between them. Preferably each of the rods 8 is so positioned as to support the tread of one of the step members. The parts so far described form no part of the present invention.

55 Each of the step members comprises a tread

or tread supporting portion 10 and a riser 11 extending at right angles thereto. Each tread has an upstanding flange 12 extending the entire length thereof and interlocking with the upper portion of the riser of the 60 next lower step member, as clearly shown. Each riser is bent to provide a substantially horizontal shoulder or ledge 13, on which the outer portion of the adjacent tread may rest, as shown, and above the ledge or shoulder 13 65 there is an offset portion 14 parallel to the riser 11 and substantially vertical, the flange 12 being adapted to fit against the offset portion 14 of the adjacent step member, as shown.

At its upper end, the offset portion 14 70 is provided with a right angular flange 15, as best shown in Fig. 4. The flange 15 assists in holding the tread 16 (which may be of any material) in position. For the same purpose, each riser has an outwardly extending bend or 75 bead 17 which is about on a level with the top of the tread, as shown.

At suitable intervals, the flange 15 is provided with a series of downwardly projecting tangs 18 which are formed by cutting and 80 striking down the metal of the flange. As shown in Fig. 1, each tang 18 is nearly vertical but at its lower end is spaced slightly farther from the upstanding portion 14 than at its upper end so as to provide a narrow V-shaped recess for the reception of the upper end of the tread flange 12. The tangs 18 are shorter than the width of the flange 15 so as not to split the metal of said flange which would cause some portions of the flange to protrude 90 upwardly at the edge of the tread, which would be objectionable.

As shown in Fig. 3, when the step members are to be assembled, the tread or one member is inclined at an acute angle to the shoulder 13 95 of the other step member and the upper edge of the flange 12 is inserted between the tangs 18 and the offset portion 14. Then the tread 10 is lowered and so moved as to bring the flange 12 adjacent to the portion 14, whereupon the upper edge of the flange 12 will be inserted into and fit snugly within the V-shaped spaces provided between the tangs 18 and the portion 14. As the drawings clearly indicate, the parts so assembled cannot be 100 moved in any manner. For securing each tread member, it is only necessary to tighten two of the screws 7 and one of the nuts 9. The stringers will tightly compress the step members at the joints thereof and any strain 105

put upon the steps themselves would be transmitted directly to the stringers which are of ample strength to support whatever load may be placed upon them, without sagging or buckling.

The treads 16 may be positioned either before or after erection of the steps, according to what material they are made of, and as they are clamped between the stringers they have a definite tendency to strengthen the tread portions 10 and also strengthen the joints between adjacent step members. If, for any reason, the step members need to be disassembled, this may be done by removing the rods 8 and the screws 7 and by lifting the treads one at a time, in the manner indicated in Fig. 3, to bring the flanges 12 out from under the tangs 18.

It will be appreciated that the very simplicity of the invention is its chief virtue. The steps of the described construction are not only very easy to manufacture and assemble, but are quite economical because the formation of the tangs involves only a very simple operation which may be performed at the time the sheet metal members are made.

Obviously the present invention is not restricted to the particular embodiment thereof herein shown and described.

30 What I claim is:—

1. In a stair construction, in combination, a plurality of assembled and interlocking metal members each consisting of a tread portion and a riser portion; each tread portion having an upstanding flange; each riser portion having a shoulder for the support of the adjacent tread portion, an upright offset portion against which the aforesaid flange may be abutted, and a flange projecting over the upper edge of the upstanding flange of the adjacent tread portion; the flange last named having projecting tangs struck out from the metal thereof and extending downwardly and

spaced sufficiently far from the upright offset portion to receive the upstanding flange of the 45 tread portion; the tangs preventing outward movement of each riser and inward movement of each tread; the parts being so constructed and arranged that assembly is effected by an arcuate movement of each tread to bring the 50 upper edge of its upstanding flange between the tangs and the offset portion aforesaid.

2. In a stair construction, in combination, a plurality of assembled and interlocking metal members each consisting of a tread portion 55 and a riser portion; each tread portion having an upstanding flange; each riser portion having an upright offset portion against which the aforesaid flange may be abutted, and a flange projecting over the upper edge 60 of the upstanding flange of the adjacent tread portion; the flange last named having projecting tangs struck out from the metal thereof and extending downwardly and spaced sufficiently far from the upright offset portion 65 to receive the upstanding flange of the tread portion; the tangs preventing outward movement of each riser and inward movement of each tread.

3. A metallic unit for the formation of 70 stairs, comprising, in combination, a strip of sheet metal bent substantially medially to provide a tread or tread-supporting portion, which is horizontal, and a riser, which is substantially vertical; a flange extending along 75 the margin of the tread portion; the upper end of the riser portion being shaped partly to enclose the flange of a similar unit when the units are assembled; and tangs struck out from the upper end of said riser portion and 80 so shaped and arranged as to prevent lateral movement of the units when assembled.

In testimony, that I claim the foregoing as my own, I have hereto affixed my signature.

ELMER HEDEEN.
